UNITED STATES PATENT OFFICE.

JOHN W. BURKETT, OF COLUMBUS, OHIO, ASSIGNOR TO THE BURKETT MANUFACTURING COMPANY, OF COLUMBUS, OHIO, A CORPORATION OF OHIO.

INTERNAL-COMBUSTION ENGINE.

1,253,933.

Specification of Letters Patent. Patented Jan. 15, 1918.

Application filed January 29, 1916. Serial No. 75,160.

To all whom it may concern:

Be it known that I, JOHN W. BURKETT, a citizen of the United States, residing at Columbus, in the county of Franklin and 5 State of Ohio, have invented certain new and useful Improvements in Internal-Combustion Engines, of which the following is a specification.

This invention relates to internal combustion engines and is directed principally to 10 the provision of an improved type of valve structure for governing the admission to and exhaust from the engine cylinder. In this connection, the main object of my invention resides in the provision of a single 15 valve, by means of which both the fresh and the burned gases are effectively controlled to and from the engine cylinder.

A further object of my invention resides 20 in a structure of this type whereby leakage of the gases from the cylinder, especially on the compression stroke, is effectively overcome. In doing this, I also so arrange this structure that the moving parts are well 25 lubricated and also may be maintained in a comparatively cool state.

Still a further object of my invention resides in the combination of a sleeve valve and a puppet valve, the puppet valve being 30 the primary valve, by means of which the gases to and from the engine cylinder are controlled. The sleeve valve is arranged to uncover the exhaust and intake passages at the proper time, while the puppet valve 35 itself is arranged to control these gases as far as the engine cylinder directly is concerned. By this arrangement, both the exhaust and the intake gases must pass the puppet valve and by means of this the puppet 40 valve is cooled to an appreciable extent by coming in direct contact with the incoming gases on the suction stroke of the engine and further, these incoming gases are heated to an appreciable extent to assist 45 vaporization by coming in contact with the comparatively warm puppet valve. It will, therefore, appear that a two-fold purpose is accomplished, that of keeping the puppet valve in a state of coolness which will prevent 50 its warping and also of assisting vaporization by subjecting the incoming gases to an additional heat as they enter the engine cylinder.

Other objects of my invention will become 55 more apparent after a further detailed de-

scription of the accompanying sheets of drawings, in which similar characters of reference designate corresponding parts, and in which:

Figure 1 is a vertical section taken through 60 the end of the cylinder carrying my improved valve structure.

Fig. 2 is a side elevation of the structure shown in Fig. 1.

Fig. 3 is a top plan view of the valve 65 actuating mechanism as shown in Figs. 1 and 2.

Fig. 4 is a section taken on line 4-4 of Fig. 1, and,

Fig. 5 is an end elevation of the structure 70 shown in Figs. 1 and 2.

In these several views, the engine cylinder is shown at 1 and this cylinder is provided with a hopper 2, which contains the cooling water, the cylinder and the remaining parts 75 being jacketed to permit the flow of water from the hopper 2 into the various jacketed portions. Instead of having a removable head for the engine cylinder as is customary in a great many instances, I have made this 80 head integral with the cylinder and provided the same with an exhaust passage 3 and an intake passage 4 into which pipes 5 and 6 respectively, are threaded, which lead to the muffler or directly into the atmosphere and to the carburetor generator 85 respectively. Both of these passages communicate with a common passage preferably disposed in the center of the cylinder head, as is shown, and it is within this common passage that the valve mechanism is 90 itself located.

This valve mechanism comprises a cage member 7 closed at its outer end as is shown at 8 and open at its inner end and formed 95 at its inner end with a valve seat, as is shown at 9. This valve seat is preferably of the tapered type, which taper leads in such direction that the valve 10 operating in conjunction with it, is pressed thereagainst by the compression within the cylinder itself. This cage is also provided with a series of spider arms 11 at its inner end and this head 8 is apertured to slidably receive the valve stem shown at 12, it being 100 this valve stem 12 which carries the puppet valve 10 at its inner end. The cage 7 is further slotted at its upper and lower sides as is shown at 13 and 14 respectively, to be in alignment with the respective exhaust, 105 110

and intake passages 3 and 4. Mounted in coöperative relation with the cage 7 and supported thereon is a hollow sleeve valve 15, which sleeve is provided with the slotted openings 16 and 16^a. This sleeve is made to have a working fit with the engine frame and also with the cage, while its outer end projects beyond the engine framework and is provided with a segmental rack such as is shown at 17. The manner of operation of the sleeve valve is such that its opening 16^a passes the intake passage 4 during the suction stroke of the engine and the opening 16 passes the exhaust passage 3 during the exhaust stroke of the engine. Meanwhile, suction created by the down stroke of the engine piston causes the puppet valve 10 to open to permit the influx of a fresh charge, while on the exhaust stroke, mechanism is provided for positively opening this puppet valve to permit the out-flow of the exhaust gases. In this manner, both the intake and exhaust gases pass the valve 10 and, therefore, the heat interchange described in the foregoing part of this specification, will take place. It will be noted also that the puppet valve 10 opens in such direction that the pressure within the engine cylinder on the compression and expansion stroke will tend to force this valve 10 against its seat 9 to prevent leakage and in order to prevent leakage between the cage 7 and the engine framework, I have provided this sleeve with an annular shoulder 18 whose tapered face coöperates with a similarly formed shoulder and face 19 of the engine framework. It is desirable that the coöperating faces formed by the shoulders 18 and 19 should be made very exact, which may be accomplished by grinding, or they may be suitably packed in order to prevent leakage of the gases from the engine cylinder through this point of connection. It will, therefore, appear that if this joint between the surfaces formed by the shoulders 18 and 19 is made tight in any one of a number of practical ways in which this may be accomplished, the compression within the cylinder will always be held, inasmuch as it is only about the valve 10 that these gases can then escape. This valve is held against its seat by the internal pressure within the cylinder and is further prevented from warping by the cooling effect produced by the incoming gases and by the cooling effect of the water in the jacket space 20.

The actuating mechanism for the valve structure will now be described: It is desirable that the cage 7 should be held tightly in position to prevent its rotation and also to have a wedging bearing between the surfaces formed by the shoulders 18 and 19. This is accomplished by means of the frame piece formed by the arms shown at 21, 22 and 23, the arm 22 being provided with a

hub 24 through which the valve stem 12 passes. This hub is made to bear against the head 12 of the cage 7 by tightening of the bolts or screws 25, which hold this frame piece in position and in this manner the cage may be wedged against its seat the desired extent. This three arm framework is further provided with a rearward extension 26, which extension is L-shaped in general contour as is shown particularly clearly in Fig. 3, the portion 27 of this extension lying in central alinement with the center of the valve structure as a whole and the engine cylinder and being bored to slidably receive the valve stem 12. This valve stem continues rearwardly from this point and is provided at its outer end with a washer shown at 28. A spring 29 is located between the portion 27 of the three armed framework and the washer 28, in order that the valve 10 may always be held against its seat. This spring has a tension sufficient to always seat the valve 10, but is also weak enough so that the suction stroke of the engine will open the valve to permit the inflow of gases. It will be noted that this may be very readily accomplished, inasmuch as the spring 29 is located at a point remote from the intense heat created by the burning gases and, therefore, it will retain its temper.

The mechanism provided for positively opening the puppet valve 10 on the compression stroke, comprises a finger 30 rigidly secured to the valve stem and arranged in such position to be engaged by the cam surface 31 carried by an arm 32 which latter is integrally formed with the casting shown at 33. It will be noted that this cam surface is so inclined that the upper edge will be the initial portion to strike the finger 30 and because of the slower rate of movement of this portion as compared with the farther end, there will be less likelihood of a pound. After the upper portion has come into engagement, the remainder will gradually contact with the finger 30 as the arm 32 continues to swing in a forward direction. This latter casting 33 is rotatably mounted on a stub shaft 34 rigidly secured to the L-shaped extension 26. This casting 33 is further provided with a segmental gear, shown at 34, designed to mesh with the segmental rack 17 and also with a down-standing arm 35 which is designed to be connected to the rod shown at 36, which latter runs to any desired portion of the engine mechanism for giving the desired valve motion. It will be noted that the motion desired is that of either an eccentric or crank, so that the rod 36 will be given a movement back and forth.

The manner of operation of the actuating mechanism is as follows: A pull on the rod 36 will rotate the sleeve valve in a counter clockwise direction, which brings the slot 130

16 opposite the exhaust passage 3 and breaks the connection of the slot 16^a with the intake passage. Before the piston has reached the end of its exhaust stroke, the rod 36 will 5 have begun a rearward movement, so that at the end of the exhaust stroke the slot 16^a will be in a position just preceding its communication with the intake passage 4. Therefore, on the intake stroke this slot will

10 move past the intake passage and the communication between the exhaust passage and the cylinder will be broken. This oscillatory movement is maintained throughout the continued operation of the engine and in 15 this manner the intake and exhaust gases are controlled as has been previously related.

What I claim, is:

1. In an internal combustion engine provided with intake and exhaust passages, a 20 common passage leading into the engine cylinder and communicating with both the intake and exhaust passages, a cage member located within said common passage and provided with a valve seat at its inner end, a 25 hollow sleeve valve supported by said cage member, means for turning said sleeve valve in such manner to uncover said intake and exhaust passages in their proper order, and a primary valve working on the valve seat of 30 said cage.

2. In an internal combustion engine provided with intake and exhaust passages, a common passage leading into the engine cylinder and communicating with both the in-

take and exhaust passages, a cage member located within said common passage and provided with a valve seat on its inner end, a hollow sleeve valve supported on the exterior of said cage member, means for imparting a turning motion to said sleeve valve to uncover 35 said intake and exhaust passages in their proper order, and a primary valve working in the valve seat of said cage. 40

3. In an internal combustion engine provided with intake and exhaust passages, a 45 common passage leading into the engine cylinder and communicating with both the intake and exhaust passages, a cage member located within said common passage and provided with a valve seat on its inner end, 50 a hollow sleeve valve supported by said cage member, means for imparting a turning motion to said sleeve valve to uncover said intake and exhaust passages in their proper order, a primary puppet valve working on 55 the valve seat of said cage, a stem on said puppet valve slidably supported in said cage member and projecting out through the rear end thereof, and resilient means operatively engaging the end of said stem projecting out 60 of the rear of said cage member.

In testimony whereof I affix my signature in presence of two witnesses.

JOHN W. BURKETT.
